UNITED STATES PATENT OFFICE

RICHARD D. SMITH, OF ANDOVER, VIRGINIA

SAFETY DROP-DOOR HOOK

Application filed April 26, 1930. Serial No. 447,548.

This invention relates to safety means for use in connection with the drop doors of hopper cars employed in the transportation of coal, coke, ballast and commodities handled 5 in bulk.

Usually, the drop doors are operated by a winding mechanism which is generally relied upon to hold the door closed against the stress of the load, but it frequently happens that the weight of the load under jar and vibration disables the winding mechanism and permits the door to open and dump the load.

The present invention guards against an 15 emergency of the nature stated and supplies a hook, of peculiar formation, which acts independently of the accustomed winding mechanism to hold the door closed and sustain all stresses tending to force the door 20 open.

The invention, furthermore, provides a member coacting with the hook to hold it in one of three positions, locked, neutral and elevated, and which may be readily adjusted 25 to the desired position to admit of the door opening, closing or being free to swing in either direction.

While the drawings illustrate the preferred embodiment of the invention, it is to be understood that in adapting the means to meet specific needs and requirements, the design may be varied and changes in the minor details of construction may be resorted to within the scope of the invention as claimed, 35 without departing from the spirit thereof.

For a full understanding of the invention and the merits thereof, reference is to be had to the following description and the drawings hereto attached, in which:

40 Figure 1 is a side view of an end portion of a hopper car, illustrating an embodiment of the invention.

Figure 2 is an enlarged view of the chute, 45 parts being broken away to show the ordinary winding mechanism associated with the drop door and depicting an application of the safety hook forming the invention.

Figure 3 is a fragmentary sectional view 50 on the line 3—3 of Figure 2.

Figure 4 is a detail view showing the safety hook locked.

Figure 5 is a similar view showing the safety hook released, and the member coacting therewith in neutral position.

55

Figure 6 is a view of the parts illustrated in Figures 4 and 5, showing the safety hook elevated to permit of unobstructed opening and closing of the drop door.

Figure 7 is an enlarged sectional view on 60 the line 7—7 of Figure 4.

Figure 8 is a modification showing the hook and coacting member provided with teeth to prevent displacement.

Figure 9 is an enlarged fragmentary sec- 65 tional view on the line 9—9 of Figure 1.

Corresponding and like parts are referred to in the following description and designated in the several views of the drawings by like reference characters.

70

The numeral 1 designates the body of a hopper car utilized for hauling commodities in bulk and provided in its bottom with chutes 2 for discharge of the load. Each of the chutes 2 is provided with the usual drop door 3 which is hinged at the top to swing outwardly to open position at the bottom, as indicated by the dotted lines in Figure 2. Referring to Figures 2 and 3 of the drawings, the numeral 4 designates the winding mechanism associated with the doors 3 for effecting an opening and a closing thereof. This winding mechanism is ordinarily depended upon to maintain the door closed against the thrust of the load and should it give way, the door opens and discharges the load.

In accordance with the present invention, a safety hook 5 is provided and is pivoted to the outer side of the chute 2, it being understood that each side of the car is similarly equipped with a hook. A batten 6 is located adjacent the lower end of the door 3 and in accordance with the present invention, this batten is of a length to be engaged by the hook 5, as indicated most clearly in the several views of the drawings. The pivot 7 upon which the hook 5 is mounted may consist of a rivet, bolt or other fastening, the pivotal end of the hook 5 being recessed in its top 85 90 95 100

side, as indicated at 8. The recess is of semi-circular outline and defines two horns or extensions 9 and 10, and is located opposite the pivot 7 with the result that the horns or extensions 9 and 10 are disposed upon opposite sides of a line passing perpendicularly through the pivot 7.

A member 11 coacts with the safety hook 5 and is eccentrically pivoted disposed opposite the recess 8 to lie therein to hold the safety hook 5 in closed position, as indicated most clearly in Figure 4, or in elevated position, as indicated in Figure 6 of the drawings. As indicated in Figure 4, the member 11 abuts 15 the horn or extension 9 and, as shown in Figure 6, it engages the horn or extension 10. The member 11 is slightly elongated or elliptical and in either one of the positions shown in Figures 4 and 6, it engages both 20 horns or extensions but the major or active axis is in line with the element 9 in Figure 4, and with the element 10 in Figure 6, as will be readily appreciated. The member 11 partakes of the nature of a holder and is mounted upon a pivot 12 which may consist of a 25 rivet or analogous fastening attached to a side of the chute 2. A link 13 connects the outer ends of the pivots 7 and 12, thereby bracing and reinforcing the same. A filler 14 is interposed between the hook 5, member 11, and side of the chute 2, and is retained in 30 place by the pivot fasteners 7 and 12, as indicated most clearly in Figure 7 of the drawings. The engaging faces of the parts 5 and 35 11 may be plane or toothed, as indicated in Figure 8, and in the latter instance, displacement of the parts is prevented, as will be readily comprehended.

When the drop door 3 is closed and the 40 safety hook engaged over the batten 6 and the hook made secure by the member 11, as indicated in Figure 4, accidental opening of the door is prevented. When the member 11 is adjusted to a neutral position, as indicated 45 in Figure 5, the door, if open, may be swung into closed position, and the hook will ride upon the batten 6 and automatically engage thereover and lock the door. When the member 11 is adjusted to the position indicated in 50 Figure 6, the hook 5 is held elevated and out of the path of the batten 6, so that the door 3 may swing freely and unobstructedly into open or closed position. The safety hook may be used in conjunction with the usual winding mechanism or independently thereof, and 55 serves in conjunction with the member 11 to lock the door against accidental opening, as will be readily understood.

What is claimed is:

60 1. Safety means for a drop door, comprising a hook having a recess of approximate semi-circular outline in its upper side at its pivotal end, and a member eccentrically mounted above the hook in position to engage the said recess to admit of holding the hook

in locked position, elevated, or in neutral position.

2. A safety hook for drop doors provided with a semi-circular recess opposite the pivot of the hook, and a member mounted eccentrically and adapted to coact with the hook to hold it in locked position, elevated, or in neutral position. 70

3. A safety hook of the character specified pivotally mounted and having a semi-circular recess opposite the pivot, and a member eccentrically mounted and engageable with the recess and having a major axis adapted to positively engage either end of the recess to hold the hook locked or elevated. 75

4. The combination with the drop door of a hopper car, of a safety hook formed with a semi-circular recess, a holding member engageable with the recess of the hook, pivots connecting the hook and holding member to the car, and a link connecting the outer ends of the pivots. 80

5. The combination with the drop door of a hopper car, of a safety hook formed with a semi-circular recess, a holding member engageable with the recess of the hook, pivots connecting the hook and holding member to the car, a link connecting the outer ends of the pivots, and a filler between the car and the hook and holding member and retained 95 in place by the pivot fastenings. 90

In testimony whereof I affix my signature.
RICHARD D. SMITH. [I. s.]
